UNITED STATES PATENT OFFICE.

EDWARD SCHULER, OF SPRINGFIELD, ILLINOIS.

SCAFFOLD.

Application filed September 15, 1922. Serial No. 588,443.

This invention relates to scaffolds or stages designed for use by workmen employed in working upon buildings and has for its object the provision of a novel device which is placed in position from the ground and which therefore renders it unnecessary to climb out upon the roof to affix any supports.

An important and more specific object is the provision of a device of this character which includes a vertical support adapted to be held in spaced relation to the side of a building and carrying a carriage which is vertically movable by means of block and tackle operated by a workman using the device, the upright support being held in position by adjustable inclined brace members which engage upon the ground.

A further object is the provision of a device of this character which is so constructed that the brace member may be placed at different positions so as to vary its angle with respect to the vertical support and the side of the building.

An additional object is the provision of a device of this character which will be simple and inexpensive in manufacture, easy to place in position and use, efficient and durable in service and a general improvement in the art.

With the above and other objects and advantages in view the invention consists in the details of construction to be hereinafter more fully described and claimed and illustrated in the accompanying drawings, in which:—

Figure 1 is a side elevation of the device in position,

Figure 2 is a front elevation thereof,

Figure 3 is a perspective view of the supporting member at the top of the inclined brace,

Figure 4 is a cross section on the line 4—4 of Figure 1,

Figure 5 is a detail view of the slideable carriage,

Figure 6 is a side elevation of a modified form of slideable carriage,

Figure 7 is a detail section on the line 7—7 of Figure 6,

Figure 8 is a detail view of an element of this modified construction, and

Figure 9 is a horizontal section taken on the line 9—9 of Figure 5.

Referring more particularly to the drawings the letter A designates the side of a

building and B designates a portion of the roof thereof. It is to be observed that the entire device is designed for use in connection with buildings of that type which have no bulletin board, the type being illustrated. In carrying out the invention I provide an upright designated broadly by the numeral 25 and formed of telescopic sections 26 and 27 rectangular in cross section and held together as by means of a latch member 29 engaging through registering ones of a plurality of holes 30 in the sections. It is intended that two upright members be used and they may be spaced any desired distance apart depending upon the length of stage to be used as will be hereinafter explained. Carried by the upper extremity of the upper section 27 is a head 31 formed with an apertured bracket 32 for a purpose to be described.

The means for supporting the upright member 25 consists of a brace device including a base portion designated broadly by the numeral 33 and including spaced bars 34 connected at intervals by cross plates 35 and having secured to their lower ends diverging legs 36. The side bars 34 are each provided with a series of holes 37. Slidable between the bars 34 of this base member is a bar 38 held in adjusted position by means of a pin 39 which passes through selected ones of the holes 37 and through a hole in the bar 38. At the upper end of the bar 38, which is formed hollow is secured a bracket 40 carrying a pulley 41 about which is trained a flexible member 42 which extends down to the ground at one end and which has its other end connected with the lower end of a channel bar 43 slideable within the bar 38, and the purpose of the flexible member 42 is to pull the bar 43 upwardly out of the bar 38 and to hold it in such adjusted position. The channel accommodates the flexible member. Also connected with the bar 38 is a bracket 44 with which is connected one end of a rope or the like 45 which may be pulled upon to lower the bar 38 between the bars 34 in case it should bind from any reason and fail to drop gravitationally upon removal of the pin 39.

Secured upon the upper end of the bar 43 is an inclined bar 46 adapted to be engaged against the side wall A of the building. Depending from this bar 46 is a hook 47 which engages within a hole in the head 31 at the top of the upright section 27.

Associated with the lower end of each upright member 25 is a steadyng device designated broadly by the numeral 48. This member comprises a pair of spaced bars 49 which are each provided with a plurality of holes 50 and which have their end portions laterally and then right angularly offset as shown at 51 for engagement against the side of the building. The bars 49 are held in proper spaced relation by a bar 52 which is secured to the offset end portions as clearly shown. Associated with the bars 49 are brackets 53 having right angularly bent ends 54 slotted for slidble engagement upon the bars 49, and these brackets are each formed with a hole adapted to register with selected ones of the holes 50. Disposed inwardly of the brackets 53 is a U-shaped bracket 55 secured thereto and likewise having its arms formed with holes. This U-shaped member is relatively long and is adapted to slidably engage against the upright 25. A pin 56 is employed for passing through the registering holes for holding this steadyng member in proper adjusted position upon the upright 25 and this pin is provided at one end with a ring head 57 and at its other end with a cotter pin or the like 58 whereby to prevent accidental withdrawal.

Slidably mounted on the upright 25 is a carriage designated broadly by the numeral 60, which carriage includes an upper portion constructed of a member 61 which has its rear end secured to a vertical bar 63. The carriage further includes a lower portion formed of a pair of bars 62 of angular formation at the rear ends of which is suitably journaled a roller 62^a. The carriage further includes a vertical member 66^a terminating in an eye 66 at its upper end and having its intermediate portion secured to the bars 61 as shown at 66^b. Secured to the lower portion of the bars 63 and 66^a is an angular frame 60^x including outwardly extending angular brackets 66^a which are suitably slotted and through which the bars 62 are slidably mounted for adjusting purposes. Holes 62^a are provided in the bars 62 and corresponding holes 50 are of course provided in the angular frame or bracket member 68 for the passage of a pin 62^c or the like whereby these elements may be held in the desired relatively adjusted positions. The angular frame or bracket structure 60^x is secured to a horizontally extended bar 62^b which has an upturned forward end portion 62^e with which is connected a diagonal brace bar 64 which is in turn connected at 64^a with the member 61. Journaled within the confines of the intermediate portion of the angular frame or bracket structure 60^x are spaced rollers 66^a designed to bear against opposite sides of the upright 25 during vertical movement of the entire carriage. The above described eye

66 is provided for the purpose of permitting engagement therein of whatever hook or other fastening is provided on the lower pulley blocks 67 which form part of a block and tackle structure further including a pulley block 68 suspended from the bracket 32.

Pivoted at 70 upon the inclined bar 46 is a bar 71 which is pivotally connected at 72 with a depending inclined brace 73 which is slidble through the bar 46 and which is formed with notches 74 selectively engageable upon a pin 75, this structure permitting adjustment to bring the bar 71 into horizontal position for the purpose of supporting a board, ladder or the like.

In Figures 6, 7 and 8 I have shown a modification of the slidble carriage in which the numeral 80 designates an upright arm terminating in an enlargement 81 formed with a hole 82 and a notch 83, either of which may be used for attachment of the lower pulley block 67. At its lower end this arm carries a U-shaped bracket 84 upon which is journaled a roller 85 and which has its arms formed with holes through which may be passed a pin 86 held against withdrawal as by a cotter 87 or the like. Secured outwardly of the bracket 84 at its connection with the arm 80 are angle plates 88 through which are slidble the arms of a U-shaped yoke 89 which has its bight portion carrying a wheel or roller 90 adapted to bear against the side of the building worked upon. The arms of this yoke 89 are formed with holes 91 which may be selectively brought into registration with the holes in the bracket 84 so that the pin 86 may be inserted through these registering holes for maintaining adjustment.

Carried by the lower end of the arm 80 is an L-shaped bar 92 with the free end of which is connected a brace 93 which extends diagonally upward and which is connected with a U-shaped bracket 94 which straddles the arm 80 and within which is mounted a roller bearing 95. The open portion of the bracket 94 has extending thereacross a removable pin 96 held against withdrawal by a cotter or the like 97.

In the above described modification it will be apparent that the rollers 85 and 95 bear against the upright 25. When it is desired to disconnect the carriage from the upright it is merely necessary to withdraw the pin 96 and also the pin 86 whereupon separation may be effected while the upright is in place and while the carriage is suspended. In the use of the device two are employed and it will be seen that the members 38 and 43 of each are longitudinally adjusted to bring the angular upper ends 46 against the side of the building at the desired location. The adjustment of the members is effected by pulling upon the cables 42 as will be obvious and the adjusted

position is maintained by tying or otherwise securing the free ends of the cables. The uprights 25 are of course supported from the inclined or angularly offset upper ends 5 46 by means of the hooks 47 described and it is to be noted that the lower ends of the uprights 25 are held spaced from the side of the building by the steadyng members.

Assuming that everything has been assembled and applied as above described and that a ladder or board is placed from one carriage member to the other, the workman takes his place upon the platform and can control the height of the stage by manipulating the block and tackle. It will be seen that there is no necessity whatever for getting out on the roof of the building to effect placing of any of the parts and it is also obvious that the device is held in position 20 without the use of any securing members whatever which would mar or deface the side of the building. Another feature of advantage is that the various parts of the device are quickly and easily capable of dis- 25 assembling and may occupy but very little room in transportation or storage.

From the foregoing description and a study of the drawings it will be apparent that I have thus provided a simply constructed and consequently inexpensive scaffold or stage device which will be highly advantageous for the purpose specified and which will efficiently perform all the functions for which it is intended.

While I have shown and described the preferred embodiment of the invention it is of course to be understood that I reserve the right to make such changes in the form, construction and arrangement of parts as

will not depart from the spirit of the invention or the scope of the subjoined claims.

Having thus described my invention I claim:—

1. A device of the character described comprising an extensible inclinable brace member having its upper end obtusely inclined and designed for engagement against the side of a building, means for supporting a stage from the upper end of said brace member, an arm pivoted at one end upon the upper end of said brace member, a brace rod pivotally connected with the free end of said arm and having its lower edge serrated, a projection on the inclined end of the brace rod engageable by a selected serration 55 whereby to hold said arm in horizontal position for holding a stage or platform horizontally regardless of the angular position in which the brace member may be placed.

2. In a structure of the character described, a support, an extensible bar adjustably connected with the support and having an angular upper portion adapted for disposition against the side of a building, means for adjusting the extensible bar and maintaining it in selected position, an arm pivoted on the angular upper end of the extensible bar and adapted to constitute a support for a platform, a brace pivotally connected with said arm and having its edge 70 serrated, and an element carried by the angular end of the extensible bar engageable by a serration for holding the arm in horizontal position.

In testimony whereof I affix my signature.

EDWARD SCHULER.
